UNITED STATES PATENT OFFICE.

RAY W. FRANKLIN, OF MONTICELLO, IOWA, ASSIGNOR TO FRANKLIN BARN EQUIPMENT COMPANY, OF MONTICELLO, IOWA, A CORPORATION OF MAINE.

RAIL AND CABLE CONNECTION.

1,317,695.

Specification of Letters Patent.

Patented Oct. 7, 1919.

Application filed February 19, 1919. Serial No. 278,011.

To all whom it may concern:

Be it known that I, RAY W. FRANKLIN, a citizen of the United States of America, and a resident of Monticello, Jones county, 5 Iowa, have invented certain new and useful Improvements in Rail and Cable Connections, of which the following is a specification.

My invention relates to improvements in 10 rail and cable connections, and the object of my improvement is to provide securing and supporting connecting means between a solid rail track of the suspended type and a cable so constructed as to permit a 15 wheeled carrier to move smoothly and without jarring or interruption over the joint of the rail and cable.

This object I have accomplished by the 20 means which are hereinafter described and claimed, and which are illustrated in the accompanying drawings, in which Figures 1 and 2 are respectively front and rear elevations of the connecting and supporting means of my invention for the adjacent extremities of a track-rail and a cable; Fig. 3 is a top plan view of the same; Fig. 4 is 25 an end elevation of the adjustable bracket-hanger, showing the track-rail, cable, and connecting-means therefor in cross section; Fig. 5 is a detail perspective view of the cable-hook engaging face of the clamping plate; Fig. 6 is a detail elevation of the cable-hook or loop, showing it positioned 30 upon a section of the fixed track-rail; Fig. 7 is a detail elevation of the opposite side of 35 said cable-hook, showing it in engagement with the clamping plate boss, as located between said plate and said rail-section, with parts of the latter broken away.

Similar numerals of reference denote corresponding parts throughout the several views.

The numeral 9 denotes a rafter of any 40 building, such as a barn, and the numeral 45 1 denotes a fixed depending part of a bracket hanger supported on said rafter. The part 1 has a tri-formed vertical slot 2 forming a guide-way into which the T-shaped hanger part 5 with its medial web 50 4 telescopes, said part having a lug or projection 7 to receive a lateral brace 31. Said hanger parts 1 and 4 have pluralities of spaced bolt-holes 14 and 14', respectively,

for receiving bolts 11 secured by nuts 12, whereby the hanger part 5 may be adjusted 55 vertically relative to the part 1, as desired. The T-shaped part 2—5 telescopes easily within the tri-form groove in the upper hanger parts 1 and 3 without danger of oscillation horizontally. 60

The lower portion of the hanger part 5 is widened, then curved forwardly and supplied with an integral terminal which is flattened and bent in a vertical plane 6 having a plurality of bolt holes to receive the bolts 13. 65

The numeral 15 denotes a clamping plate of elongated form, whose rear face is flattened to conform to the flat vertical plane of the hanger part 6, fitting same, and having cross ribs 16 to engage the opposite ends of 70 the part 6 to prevent relative displacement. The forward face of the plate 15 has a medial longitudinal rib or boss 29 with ends spaced from the ends of the plate, the plate, including said rib 29, having an alined row of bolt 75 holes 30 to receive said bolts 13.

The numeral 26 denotes part of a suspended wire cable having a terminal hook or loop part 27 of elongated form, whose cavity is fitted by the inserted elongated boss 29 on 80 the clamping plate 15. The numeral 8 denotes a brace rod whose lower end is clamped into an orifice in a side of the lower widened part of the hanger body 5. The rod 8 has its upper end secured to the rafter 9 by 85 means of a tension bolt 10, thus permitting an adjustment of the tension of the cable.

I have shown a solid track rail made up of alined sections, such as the sections 17 and 19. The track rail is of the I-beam type, but 90 may be of any other desired or suitable section, and the abutting ends of the sections thereof may be fixedly connected in alinement by means of a pair of clamping plates 20 secured by bolts 21 and nuts 28. The terminal rail section 17 has a plurality of longitudinally alined bolt holes 18, and said section 17 is positioned longitudinally over and in contact with the loop-part 27 of said cable and is fixedly secured thereto and to 100 the clamping plate 15 and hanger part 6 by means of said bolts 13 and nuts 28.

The numeral 24 denotes that portion of the connection which permits a smooth approach of the carrier. One end is flexibly 105 connected in alinement with the outer end

of the rail section 17 by specially designed clamping plates 22 secured by tight-and-loose bolts 23 in such a way as to permit a hinged action of part 24 to conform with variations of cable as wheeled carrier passes over the approach or part designated as 24.

The cable 26, in extending outwardly from its looped extremity, is passed through the hollow sleeve 24, the outer end of the sleeve being sloped and contracted to fit the cable closely and thus provide a gradual transition member between the rail 17 and the cable, and a bolt 25 is used to secure the contracted outer end of said sleeve to the cable. It will be seen, therefore, that while the cable is not directly in line with the rail section 17, the sleeve 24 provides intermediate means for the passage of the wheels of the litter carrier, or the like, smoothly and without jar or interruption from one of the connected bodies to the other.

The connecting means described are such as to aline and connect accurately and securely the track rail and the cable and effect a secure anchorage to the adjustable hanger.

Having described my invention, what I

claim as new, and desire to secure by Letters Patent, is:

In combination, a hanger, a rail, a flexible approach device, and a cable, said rail and cable being supported in alinement, and connecting-means between said elements, comprising a plate positioned across the hanger and grooved to receive one extremity of the cable, the adjacent end of the rail being overlaid upon said cable-end and plate, and means for detachably securing said elements fixedly together at the lower jaw of the hanger, the flexible approach being grooved to bolt over the cable and hinged to said track rail by clamps to conform readily to the variation of the cable and effect a smooth approach thereto to eliminate jar or jolting to the carrier as it passes over the connection.

Signed at Monticello, Ia., this 31st day of January, 1919.

RAY W. FRANKLIN.
